P. K. TOPALE

RADIATOR

Filed Oct. 27, 1920

Attorney
P. K. Topale

By James J. Parker

attorney

UNITED STATES PATENT OFFICE.

PETER K. TOPALE, OF PHOENIX, ARIZONA.

RADIATOR.

Application filed October 27, 1920. Serial No. 419,891.

To all whom it may concern:

Be it known that I, PETER K. TOPALE, citizen of the United States, residing at Phoenix, in the county of Maricopa and 5 State of Arizona, have invented certain new and useful Improvements in Radiators, of which the following is a specification.

The present invention has reference generally to improvements in that class of inventions known as heat exchangers and more particularly relates to radiators for 10 motor vehicles.

It is the primary aim and object of the invention to provide a device of the above 15 character wherein the water conducting tubes are of novel construction, being designed primarily to afford ample cooling surface and in addition are capable of expanding to prevent bursting should the water freeze in the radiator.

More particularly this invention contemplates the provision of a radiator wherein the tubes are formed of substantial zig zag sections secured together in nesting pairs 25 while the adjacent pairs are spaced and shaped so as to form air passages for cooling purposes.

It is a more specific object of the invention to provide a radiator wherein the upper and lower end portions of one nesting pair of sections are secured in overlapping relation to the corresponding portions of the adjacent pair to provide leak proof joints at the mouths of the tubes.

Among the other aims and objects of this invention may be recited the provision of a device of the above mentioned character with a view to compactness and wherein the 40 number of parts are few, the construction simple, the cost of production low and the efficiency high.

Other objects, as well as the nature, characteristic features and scope of the invention will be more readily understood from the 45 following description taken in connection with the accompanying drawings and pointed out in the claims, forming a part of this specification.

The invention is clearly illustrated in the 50 accompanying drawings in which:—

Figure 1 is a front elevation of the improved radiator partly broken away and shown in transverse section.

Figure 2 is an enlarged transverse sec- 55 tional perspective detail of the same.

Figure 3 is an enlarged front elevation of a portion of the radiator core.

Figure 4 is a perspective of a pair of the nestable sections arranged at right angles indicating the manner of placing them 60 in nestable relation and before inclining the side portions.

Figure 5 is an enlarged fragmentary longitudinal section of the pair of sections shown in Fig. 4 when connected together. 65

Referring now more particularly to the accompanying drawings, there is provided a radiator including a frame (1) in which are disposed a lower receptacle (2) and an upper receptacle (3), the receptacles being arranged in communication with each other by means of the improved core composed of tubes (4), the construction of which constitutes the principal feature of 70 the present invention.

In reducing the improvement to practice the same may be said to consist of a plurality of peculiarly bent and vertically disposed plate-like sections (5), of suitable metal, pairs of the sections coacting to form 75 sinuous tubes for conducting water from one receptacle to the other. Each pair of nest- 80 ing sections is bent to form alternate U shaped channels (6), the sides (7) of which are disposed in parallel relation at the ends. 85

These pairs of sections are nested and the ends brazed or otherwise secured together. The medial portions of all of the channels are arranged parallel to each other while the alternate medial portions (8) of the U 90 shaped channels are crimped from points near their respective ends to form longitudinal grooves (9) which are positioned opposite the alternate outer medial portions (10) of the channels and this crimping acts to 95 incline the side portions (7) in opposite directions and at the same time spacing the portions of one section with respect to the corresponding portions of the adjacent section of the same pair so as to in conse- 100 quence provide the sinuous tubes. It is also to be noted that the crimping action in forming the grooves causes the U shaped channel portions to assume an M shape in cross section. The sections, however, re- 105

tain their desired shape at the ends.

Of course, after the nestable sections are secured in the manner described to form the tubes, a plurality of them are secured together as by brazing in the manner indicat- 110

ed, so as to leave air passages (11) therebetween. At the ends, the sides of the channels of one pair of nesting sections rest against and are secured to the medial portions of the channels of the adjacent pair of nesting sections. Between the ends of the sections, there is a further and additional coaction in that the outer surface of the inner hump of the M abut the outer face of 5 the medial portion of the outer channel (6) of the adjacent pair of nesting sections as indicated by the numeral (12). This feature assures of rigidity.

When all of the sections are assembled in 10 the manner indicated, the upper and lower end portions of the sections of one nesting pair are secured in overlapping relation as at (13) to the corresponding end portions of the adjacent section of the adjacent nesting pair for the purpose of providing leak 15 proof joints at the mouths (14) of the tubes, as is apparent.

By the provision of this particular construction and system, there is provided a 20 radiator capable of use in various climates, in that the M construction affords a greater cooling surface and is also freeze-proof, since the said construction allows ample room for expansion.

30 It is believed, in view of the foregoing description, that a further detailed description of the invention is entirely unnecessary. Likewise, it is believed that the advantages of the invention will be readily apparent.

35 Having thus fully described the invention what I claim is:—

1. In a radiator, a nestable section of 40 bendable metal of zig zag shape in cross section forming alternate symmetrical U shaped channels and having the medial portions of alternate channels crimped from points near the respective ends to form grooves.

2. In a radiator, a nestable section of 45 bendable metal of substantial zig zag shape in cross section forming alternate symmetrical U shape channels and having the medial portions of all of the channels arranged parallel to each other and the medial 50 portions of the alternate channels crimped longitudinally from points near the respective ends to form grooves.

3. A radiator of the character described

including a core formed of a plurality of sections connected together in nesting pairs 55 to form tubes, the sections being of alternate U shape channel formation in cross section and having only the medial portions of alternate sections provided with grooves to insure of the tube formation and to increase the rigidity of the core. 60

4. A radiator as claimed in claim 3 wherein in the upper and lower end portions of the sections of each nesting pair are connected to the corresponding end portions of the 65 adjacent sections to form leak proof joints at the mouths of the tubes.

5. A radiator including a core formed of a plurality of sections of alternate U shape channel formation in cross section, the sections being nested together in pairs and having their alternate medial portions provided with longitudinal grooves extending from points near their end edges to form 70 sinuous water passages between said sections, the opposite faces of the grooved medial portions forming humps for contacting with the straight medial portions of the adjacent pair of sections. 75

6. A radiator including a core formed of 80 a plurality of sections, the sections being of alternate U shape channel formation in cross section and nested together in pairs with their parallel side portions secured together at their end edges, the medial portions of alternate channels of each pair of sections being provided with longitudinal 85 grooves and the side portions being inclined medially of the end edges and spaced from the corresponding portions of the other sections to form sinuous tubes therebetween, the opposite faces of the grooved medial portions forming humps for contacting with the adjacent pair of sections to increase the 90 rigidity of the core, and the upper and 95 lower end portions of the sections of each nesting pair of sections being connected to the corresponding end portions of the adjacent sections to form leak proof joints at the mouths of the tubes. 100

In testimony whereof I affix my signature in the presence of two witnesses.

PETER K. TOPALE.
